UNITED STATES PATENT OFFICE.

W. B. JOHNS, OF UNITED STATES ARMY.

KNAPSACK.

Specification of Letters Patent No. 23,582, dated April 12, 1859.

To all whom it may concern:

Be it known that I, W. B. JOHNS, of the U. S. Army, have invented a new and useful Improvement in Knapsacks; and I do 5 hereby declare that the following is a full, clear, and exact description of the same, reference being had to the annexed drawing, forming part of this specification, in the several figures of which similar characters of 10 reference denote the same part.

Figure 1 is a view of the knapsack spread out. Fig. 2 is a view showing four knapsacks converted into a shelter. Fig. 3 is a 15 view showing knapsack folded and manner of carrying same.

The nature of my invention consists in providing a knapsack which is adapted to use as a shelter for the soldier.

The knapsack consists of a sheet of water 20 proof material A with straps *a* and *b*, and having a double row of button holes *c*, on its edges. This enables four or more of the knapsacks by being connected as shown in Fig. 2 to form a shelter. The precise manner of connecting the sheets is shown in 25 the drawing; any other that will serve the purpose being suitable.

In carrying the knapsack, the kit is in-

closed in the sheet A which is rolled up as shown in Fig. 3, and the blanket B secured 30 upon it as seen in the same figure. The knapsack is slung to a yoke piece C at its middle. At the ends of the yoke are straps *f f'* and *g g'*. The former buckle over the breast of the wearer and the hooks at the 35 ends of the latter catch the buckles *i*.

This improvement is designed principally for scouting parties, where shelter is impracticable.

I do not claim the mere connecting of 40 sheets together; nor, of themselves the devices used, but I claim as new—

The construction of knapsacks so as to be entirely separated from their slings, and with the means of uniting several together 45 and stretching them as described; so that the knapsack will perform the double function of sheltering the soldier and holding his kit; substantially as specified.

In testimony whereof I have hereunto 50 signed my name before two subscribing witnesses.

WM. B. JOHNS.
